(57) CLAIM

The ornamental design for a tablet computer case with handle, as shown and described.

DESCRIPTION

FIG. 1 is a perspective view of a tablet computer case with handle;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof; and,

FIG. 7 is a top plan view thereof.

The broken line showing in FIG. 5-7 is included for the purpose of showing environmental structure and forms no part of the claimed design.
